UNITED STATES PATENT OFFICE

CHARLES ROBERT MILLAR AND DOUGLAS SHOLTO STRACHAN, OF LONDON, ENGLAND

GRIPPING DEVICE

Application filed October 11, 1929, Serial No. 399,066, and in Great Britain October 26, 1928.

This invention relates to gripping devices and is especially conceived in its application to trucks or other vehicles that while being adapted for rope or cable haulage by a gripping device carried upon the vehicle are provided with such a device that is adapted to release the rope or cable when, for example, the truck or vehicle has arrived at a position at which it has to be released in order that it may then move under the action of gravity, but the invention is of wide application to gripping devices for other and similar purposes. It will be understood that in its application to trucks or vehicles that are adapted for rope haulage by the provision of a gripping device, the invention has among its objects to permit of the ready, instantaneous and complete disengagement of the rope, cable or other haulage member and to avoid damage or strain to the parts of the gripping device or to the vehicle or to the rope or to the haulage member such as might result on an incomplete disengagement and partial release of the vehicle as, for example, under the action of gravity upon an incline.

According to the invention we provide an inclined plane on a ramp set in a stationary position on or adjacent to the track and so located with respect to a releasing arm provided or depending from the gripping device carried by the vehicle running on the track that on the truck or vehicle passing the ramp the releasing arm of the gripping device is moved or rotated into a position at which the releasing arm ceases to serve as a stop against the rearward movement of a part with which one of the jaws or parts of the gripping device is connected, whereby under the operation of a spring the jaw or part of the gripping device instantaneously moves from the engaged position to an extent sufficient completely to release the rope, cable or haulage member.

According to the invention one jaw or part of the gripping device is so mounted that it is adapted to be adjusted in position with respect to a part on which it is mounted in such manner that upon wear of the rope or the faces of the respective jaws of the grip-

ping device the jaw or part referred to may be adjusted in position to take up the wear.

The invention comprises the features hereinafter described.

The invention is illustrated in the accompanying diagrammatic drawings by way of example.

Figure 1 is a sectional elevation of the gripping or clamping device provided according to the invention.

Figure 2 is an end elevation corresponding to Figure 1, with the fixed jaw omitted.

Figure 3 is a diagrammatic view of a railway truck fitted with the device provided according to the invention.

In carrying the invention into effect according to the construction illustrated in the drawings, a fixed jaw or abutment *a* of the gripping device is secured to a supporting or base plate *b* and the second or movable jaw *c* is carried by a spindle *d* mounted in a boss *e* slidably fitted within the bore of a cylinder or frame part *f* also secured to the plate *b*. The boss *e* is prevented from rotating in the cylinder by means of a longitudinal key *e*¹ engaging a keyway *f*¹. The boss *e* may also be provided with a flange or enlargement *e*² corresponding in diameter to a part *f*² of the bore of the cylinder of enlarged diameter within which it is received so that the extent of movement of the boss is determined by the width of the enlarged part of the bore. The cylinder may be closed by a cover plate *f*³ through which the spindle *d* passes with clearance. The lower part of the wall of the cylinder or frame part *f* is slotted to receive the pivotal end of the releasing arm *g* upon the pivot pin *g*¹ fitted in a corresponding recess in the wall of the cylinder *f*. The releasing arm *g* carries at its outer end a wheel *g*² and is adapted, in its normal position under the weight of the wheel *g*² or otherwise, to extend into the bore of the cylinder *f* and to be received into a corresponding recess *e*³ formed in the boss *e* in such position that it may register with the slot in the wall of the cylinder *f* when the boss *e* is in the inner position and the movable jaw *c* is gripping the haulage member *h* against the fixed jaw *a*. The releasing arm *g* thus acts as a stop to main-

tain the boss *e* and the jaw *c* in the engaged position against the action of a helical spring *i* tending to force the boss *e* rearwardly and disposed around the spindle *d* between a bearing bush *e*⁴ in the boss *e* and a retaining plate *f*⁴. When, however, the wheel *g*² contacts with and rides up the inclined face of the ramp *j* (Figure 8) at the determined position, the releasing arm *g* is rotated on its pivot pin *g*¹ until it passes out of the recess *e*⁵ of the boss *e*, so that the boss *e*, the spindle *d* and the jaw *c* may be retracted under the action of the spring *i* to release the haulage member *h*.

The form of the releasing arm *g* is advantageously such that it is maintained in the rotated or uplifted position by the unrecessed surface of the boss *e*, the wheel *g*² being received into one of two corresponding recesses *f*⁵ formed in the outer wall of the cylinder *f*. The releasing arm is thus maintained inoperative until the jaw *c* is again caused to engage the haulage member *h*. The haulage member *h* may be re-engaged merely by forcing the spindle *d* inwards and with it the boss *e*, so that the recess *e*⁵ in the periphery of the boss *e* may again come to lie in coincidence with the releasing arm *g* whereby the latter may again pass into position to serve as a stop to the boss *e* and to hold the jaw *c* in the position at which the haulage member *h* is engaged.

In order to permit of adjustment for wear of the jaws *c* and *a*, the spindle *d* is advantageously screw-threaded at *d*¹ to engage the correspondingly screw-threaded bore of the boss *e* and the jaw *c* is rotatably mounted upon the spindle, being maintained in position thereon by means of a collar *d*² received into a slot or recess *c*¹ of the jaw *c* and, if necessary, by a similar collar *d*³ at the rear of the jaw. The jaw *c* is constrained from rotation relatively to the jaw *a* either in the engaged or disengaged position by means of pins *c*² mounted therein parallel with the axis of the spindle *d* and slidably engaging holes in the jaw *a*, and by the overhanging face *a*¹ of the jaw *a*.

It will furthermore be understood that the outer end of the spindle *d* opposite to that at which the gripping jaw *c* is mounted is provided with a wheel *d*⁴ by which the spindle *d* may be conveniently rotated for the adjustment of the movable jaw *c* in the manner described, whereby a relative movement is possible between the spindle *d* and the jaw *c* carried by it with reference to the boss *e* carrying the spindle.

It will furthermore be understood that the oppositely disposed faces of the jaws *a*, *c* may be suitably formed with recesses in opposite positions for the accommodation between them of the rope, cable or haulage member *h*; that the cylinder or frame *f* may have a cover plate *f*⁵ at its outer end and that the

cover plate *f*⁵ at the inner end may be provided with an outwardly extending boss within which an annular cavity is formed for the reception of the helical spring *i*.

It will be understood that the plate *b* carrying the gripping device may be set in a convenient position beneath or upon the frame *b* of the truck or vehicle so that the spindle *d* carrying the movable jaw *c* of the gripping device is disposed transversely to the axis of the rope or haulage member *h* and may extend outwardly with the wheel *d*⁴ so disposed as to be convenient of access for the adjustment of the movable gripping jaw *c* for the accommodation of wear in the manner hereinbefore described.

It will be understood that the invention is not limited to the constructional features hereinbefore described but that the construction may be modified without departing from the invention.

We claim:—

1. A gripping device, comprising a fixed jaw, a movable jaw, a carrier for the said movable jaw, a supporting part in which the said carrier is slidably mounted, a release member pivoted to the said supporting part and adapted, when the gripping jaws are in the operative position, to retain the movable jaw, and an element, such as a spring, to throw the movable jaw out of the operative position when released by the release member.

2. A gripping device, comprising a fixed jaw, a movable jaw, a spindle carrying the said movable jaw, a boss by which the said spindle is supported, a fixed cylinder within which the said boss is slidably received, a release member pivoted upon the said cylinder and adapted, when the gripping jaws are in the operative position, to retain the movable jaw, and an element, such as a spring, to throw the movable jaw out of the operative position when released by the release member.

3. A gripping device, comprising a fixed jaw, a movable jaw, a spindle carrying the said movable jaw, a boss by which the said spindle is supported, a fixed cylinder within which the said boss is slidably received, an arm pivoted in the wall of the cylinder and adapted in its normal position to project into the bore of the cylinder and to engage and retain the boss when the movable jaw is in the operative position.

4. A gripping device as set forth in claim 3, wherein the boss is provided with a recess and the pivoted arm in its normal position engages the said recess when the boss has moved to the position in which the jaws are operatively engaged.

5. A gripping device, comprising a fixed jaw, a movable jaw, a carrier for the said movable jaw, a supporting part in which the said carrier is slidably mounted, the said

supporting part and fixed jaw being mounted upon the underside of a railroad vehicle adapted for haulage by a flexible member over a rail track, a release member pivoted to the said supporting part and adapted, when the gripping jaws are in the operative position, to retain the movable jaw, a ramp mounted upon the track in a position to act upon the release member to effect the release of the movable jaw, and an element, such as a spring, to throw the movable jaw out of the operative position when released by the release member.

6. A gripping device, comprising a fixed jaw, a movable jaw, a carrier for the said movable jaw, means for permitting relative adjustment of the movable jaw upon the said carrier, a supporting part in which the said carrier is slidably mounted, a release member pivoted to the said supporting part and adapted, when the gripping jaws are in the operative position, to retain the movable jaw, and an element, such as a spring, to throw the movable jaw out of the operative position when released by the release member.

7. A gripping device, comprising a fixed jaw, a movable jaw, a spindle carrying the said movable jaw, a boss by which the said spindle is supported so as to be relatively adjustable in the direction of its axis, a fixed cylinder within which the said boss is slidably mounted, a release member pivoted to the said cylinder and adapted, when the gripping jaws are in the operative position, to retain the movable jaw, and an element, such as a spring, to throw the movable jaw out of the operative position when released by the release member.

8. A gripping device, as set forth in claim 7, wherein the spindle is screw-threaded and the boss is formed with a screw-threaded bore for the reception of the spindle and the movable jaw is loosely mounted upon the spindle and constrained from rotation relatively to the fixed jaw.

CHARLES ROBERT MILLAR.
